Des. 233,263
Patented Oct. 15, 1974

233,263

HYDROTHERAPEUTIC PAD

Clifford E. Grube, Niles, Ill., assignor to
Associated Mills, Inc., Chicago, Ill.

Filed July 30, 1973, Ser. No. 383,816

Term of patent 14 years

Int. Cl. D24—04
U.S. Cl. D83—1 C

FIG. 2.

FIG. 3.

FIG. 4.

FIG. 5.

FIG. 1 is a top perspective of a hydrotherapeutic pad showing my new design;

FIG. 2 is a top plan view of the pad;

FIG. 3 is a cross-section taken on line 3—3 of FIG. 2;
FIG. 4 is a cross-section taken on line 4—4 of FIG. 2;
and

FIG. 5 is a bottom plan view thereof.

I claim:

The ornamental design of a hydrotherapeutic pad, as shown and described.
